C. BELISLE

FILLING REPLENISHING LOOM

Filed Mar. 10, 1922

Inventor:

Conrad Delisle
by R. H. Davis.

Attorney

UNITED STATES PATENT OFFICE.

CONRAD BELISLE, OF MANCHESTER, NEW HAMPSHIRE, ASSIGNOR TO DRAPER CORPORATION, OF HOPEDALE, MASSACHUSETTS, A CORPORATION OF MAINE.

FILLING-REPLENISHING LOOM.

Application filed March 10, 1922. Serial No. 542,738.

To all whom it may concern:

Be it known that I, CONRAD BELISLE, a citizen of the United States, residing at Manchester, in the county of Hillsboro and State of New Hampshire, have invented an Improvement in Filling-Replenishing Looms, of which the following description, in connection with the accompanying drawings, is a specification, like characters on 10 the drawings representing like parts.

This invention relates to looms, and more particularly to means for withdrawing the trailing end of the old filling from the shuttle when replenishment has been effected.

15 In looms of the filling replenishing type, sometimes called "automatic" looms, the filling is replenished from time to time by substituting for the old filling carrier or bobbin in the shuttle, another containing a supply 20 of filling wound thereon. When the filling is replenished, it is the usual practice to part the old filling between the cloth selvage and shuttle, so that when the old filling carrier or bobbin is ejected from the shuttle, the 25 trailing end of filling will be free to be withdrawn from the shuttle. If it be not withdrawn when the filling carrier or bobbin is ejected, it is liable to be carried into the shed and produce a defective portion in the cloth.

30 Various devices have heretofore been suggested for withdrawing the old filling end from the shuttle, and some of these have operated with fairly satisfactory results.

The present invention has for one of its 35 objects to provide a filling end withdrawing mechanism which will insure the withdrawal of the old filling end from the shuttle when the filling replenishment is effected.

40 An important feature of the present invention, therefore, consists of a filling end withdrawing mechanism mounted independently of the lay, and rendered effective when the filling is changed, to form a 45 plurality of bights in the filling between the ejected carrier and the shuttle, thereby withdrawing the filling end from the shuttle. In carrying this feature of the invention into practical effect, the two clearer members are 50 provided, both of which are mounted independently of the lay at a front portion of the loom, and one of which is extended rearwardly so that when the filling carrier is ejected from the shuttle on replenishment 55 of filling, the ejected carrier or bobbin will

drop frontwardly of the clearer member. The other or second clearer member is moved frontwardly on call for replenishment of filling, and after the filling has been changed it is moved rearwardly to engage the filling and then in another direction, downwardly in the present instance, to form a plurality of bights in the filling between the ejected filling carrier or bobbin and the shuttle, and withdraw the filling from the shuttle. The formation of the plurality of bights in the filling in a downward direction by the second clearer member acts to positively withdraw the filling in the direction most effective for that purpose.

60 Other features of the invention and novel mechanism and combination of parts in addition to the above, will be hereinafter described in connection with the accompanying drawings which illustrate one good practical form of the invention.

70 In the drawings:

Figure 1 is a perspective view of the replenishing side portions of a filling replenishing loom having the present invention 80 associated therewith; and

Fig. 2 is a vertical section through the lay and shuttle-box, showing also the filling end withdrawing mechanism in the position the parts assume as the lay beats up following a call for replenishment of filling.

85 The loom frame 1 has mounted thereon the magazine or hopper for containing filled carriers or bobbins to be transferred to the shuttle, and in the present instance the filling replenishing magazine is shown as of the rotary type, though this is not essential.

The bracket or stand 2 which supports the magazine is secured to the loom frame 90 as by the bolt 3, and supports the usual rotary hopper 4 in which filling carriers 5 are held for transfer to the shuttle.

95 Mounted on the transerrer arm or dead shaft 6 which extends laterally from the bracket or stand 2 is the transerrer 7, 100 normally held in its raised or inoperative position by a spring 8 as usual. Extending downwardly from the hub portion of the transerrer is an arm 9 to which is pivoted at 10 the dog 11 which is adapted to be engaged by a bunter on the lay when the dog has been moved to its operative or raised position as usual in this type of looms.

105 Supported at the front of the loom and extending transversely thereof is the trans-

verse or rock shaft 12, of usual construction, having an arm 13 extended therefrom and normally under the influence of a spring 14 acting to depress the arm and hold the 5 rock shaft 12 in its normal position. The rock shaft 12 is adapted to be rocked by the usual feeler or filling fork mechanism, but since these features form no especial part of the present invention, and are well understood, their illustration and detail description is unnecessary.

The arm 13, hereinbefore described, may be associated with the usual shuttle feeler 15, and through a train of mechanism of 15 usual character, including the slotted arm 16, the dog 11 will be raised to its active or operative position when the rock shaft 12 is rocked to the left or contra-clockwise, Fig. 1. This construction and operation of parts 20 is or may be of usual type, and is now well understood by those familiar with automatic looms.

The lay 17 is provided with the shuttle-box 18 which has an opening 19 in its bottom for the discharge of the filling carrier which is to be ejected from the shuttle; and similarly, the shuttle 20 is likewise provided with a bottom opening to permit the passage of the ejected filling carrier, as 30 usual.

Below the bottom openings in the shuttle and shuttle-box the lay 17 is cut away at 21 to provide a passage for the ejected filling carrier. This, too, is as usual in this 35 type of looms.

Secured to the transerrer or dead shaft 6 is the supporting arm 22 which may conveniently be secured to the dead shaft 6 by a bolt 23.

To the lower end portion of the supporting arm 22 is secured one of the clearer members which extends rearwardly therefrom and has as part thereof the filling engaging portion, frontwardly of which the 40 filling carrier passes when it is ejected from the shuttle. In the present instance the clearer member 24 with its rear end portion comprised as part thereof, is adjustably secured to the supporting arm 22 by a bolt 25 which passes through a slot 26 in the lower portion of the supporting arm 22 and a slot 27 in the front end portion of the clearer member, as hereinbefore noted. The clearer member 24 extends rearwardly and has the 45 laterally-extending portion 28 which may be provided with grooves or teeth 29, the construction being such that when the lay beats up, the clearer member will enter the recess 21 with the laterally-extending portion 28 rearwardly of the filling carrier or longitudinal axis of the shuttle-box, so that should a filling carrier be ejected from the shuttle, it will pass frontwardly of the clearer member and lay the filling frontwardly of the 55 laterally-extending portion 28.

Associated with the clearer member 24 is a second clearer member which, as a whole, is designated as 30, so mounted that on frontward movement of the lay on call for replenishment of filling, the second clearer member will be moved frontwardly of the other clearer member, and after the filling has been changed, will be moved rearwardly to engage the filling and by movement in another direction, form a plurality of bights 75 in the filling between the ejected carrier and the shuttle and withdraw the filling from the latter.

In the present instance the clearer member is pivotally supported at 31 on the clearer member 24, and has a frontwardly-extending portion 32 which underlies the end portion 33 of an actuator or arm 34 pivotally mounted at 35. The actuator or arm 34 has its other end 36 overlying the arm 13, hereinbefore described, and a light spring 37 normally tends to hold the end of the arm 36 on the arm 13, the construction being such that upon rocking movement of the transverse shaft 12, as hereinbefore described, the actuator or arm 34 will be moved about its pivotal support 35, and in the present instance, lower the end 33 of the actuator or arm.

The second clearer member 30, in accordance with the present invention, is mounted for both rocking and a frontward-and-rearward movement. To this end the frontwardly-extending portion or carrier 32 of the second clearer member is provided with 95 lug portions 38 in which is mounted the clearer arm 39 forming part of the second clearer member. A spring 40 has one end secured to the rear lug portion 38 and its front end attached to a stud 41 extending from the clearer arm 39, the construction being such that, under the impulse of the spring 40, the clearer arm 39 of the second clearer member is normally held in its rearward position with permissive movement 100 frontwardly, the lug portions 38 serving as 105 guide members for the clearer arm.

The second clearer member is provided with a laterally-extending portion 42 which may be conveniently formed as part of the clearer arm 39 by bending it laterally, as indicated, though of course this is not an essential.

Extending from the clearer member 24 in the present instance is a lug 43 between which and an arm 44 secured to the second clearer member, is a spring 45 which normally acts to hold the second clearer member in its inoperative position, or depressed in the present instance, so that as the lay moves frontwardly on each beat, it will not engage the second clearer member. In other words, the rear end portion 42 of the second clearer member is normally held in position by the spring 45, so that as the lay beats up, the 125 130

second clearer member will not be engaged by the lay and consequently, the parts will remain substantially in the position indicated in Fig. 1 during normal weaving operation.

On call for replenishment of filling, or when the filling is to be changed, the transverse shaft 12 will be rocked as hereinbefore described, thereby causing the end 33 of the 10 actuator or lever 34 to depress the front end portion of the second clearer member and raise its rear portion 42 into a position to be engaged by a part on the lay, so that on 15 frontward movement of the lay, the second clearer member will be moved frontwardly, and its rear end portion 42 will pass frontwardly of the other clearer member or its laterally-extending portion 28. As the lay reaches its front position, the filling is 20 changed as usual, and consequently the ejected filling carrier will pass frontwardly of the first clearer member or its laterally-extending arm 28. As the lay goes back after replenishment of filling, the second 25 clearer member will follow it for a part of its backward movement under the impulse of the spring 40, and until the clearer arm 39 is arrested by a stop which, in the present instance, may be the pin 41 or a shoulder 30 formed on the clearer arm, and thereupon the second clearer member, being now free from contact with the lay, will engage the filling end between the shuttle and the first clearer member, and under the dictates of 35 the spring 45 will be moved downwardly to form in the filling a plurality of bights passing over the first and second clearer members, and withdraw the filling from the shuttle. This action of the parts is represented by dotted lines in Fig. 2, wherein the 40 second clearer member is shown as having been freed from contact with the part of the lay on the backward movement of the latter, and is dropping downwardly toward its initial or normal position, thereby forming the 45 double bights in the filling *a* between the ejected filling carrier and shuttle.

On call for replenishment of filling, the second clearer member is swung about its 50 pivotal support, that its rear end may be engaged by the lay or a part carried thereby as the lay moves forwardly in order that the filling carrier ejected from the shuttle when the lay is in its front position may pass between the two clearer members as indicated 55 in Fig. 2; and in order to prevent overthrow movement of the second clearer member as it is moved into operative position on call for replenishment of filling, it may be desirable 60 at times to provide a stop for limiting the upward movement of the rear end of the second clearer member. Such stop is conveniently formed in the present instance by a finger 46 secured to the clearer member 24 and having an overhanging portion to en-

gage the second clearer member when it reaches its operative position. Likewise, it may be desirable in some cases to guide the end 33 of the actuator or lever 34 in its movement under call for replenishment of 70 filling, and to this end the supporting arm 22 has a guide portion 47 secured thereto and between which and the edge of the supporting arm 22 the end 33 of the actuator or lever travels.

The clearer member 24 is shown as rigidly secured to the supporting arm 22 and thus will be a desirable construction in most instances, but if desired it may be yieldingly held, so that in case the rear wall of the 80 opening 21 in the lay should strike the rear portion 28 of the clearer member, injury to parts will be avoided.

What is claimed is:

1. In a loom, the combination of filling 85 replenishing mechanism, the lay having a shuttle-box provided with a discharge opening for an ejected filling carrier, a support in front of the lay, a fixed clearer member mounted on the support in front of the lay 90 to enter the space in the lay below the opening of the shuttle-box as the lay beats up, a second clearer member sustained by said support and moved frontwardly by the lay on call for replenishment of filling, and 95 means for causing the second clearer member to engage the filling end and form a plurality of bights therein about the fixed and second clearer members and withdraw the filling from the shuttle as the lay goes back. 100

2. In a loom, the combination of filling 105 replenishing mechanism, the lay having a shuttle-box provided with a discharge opening for an ejected filling carrier, a clearer member at the front of the loom and extending rearwardly to enter the space below the shuttle-box as the lay beats up, a second clearer member normally below the first clearer member, means for raising the second clearer member for engagement and 110 movement frontwardly by the lay on call for replenishment of filling, and means for causing the second clearer member to move rearwardly as the lay goes back and return to its normal position to form a plurality of 115 bights in the filling and withdraw it from the shuttle.

3. In a loom, the combination with filling 120 replenishing mechanism, of a filling end withdrawing device comprising a fixed member and a movable member both mounted in front of the lay, means for positioning the movable member for engagement with the old filling between the fixed member and shuttle on call for replenishment of filling and for movement frontwardly with the lay as it beats up, and means for actuating the movable member to cause it to move rearwardly as the lay goes back to form a plurality of bights in the old filling between the 125 130

discharged filling carrier and shuttle and withdraw the old filling from the shuttle.

4. In a loom, the combination with filling replenishing mechanism, of a filling end withdrawing device comprising a fixed member and a movable member both mounted in front of the lay, means for raising the movable member for engagement with the old filling between the fixed member and shuttle on call for replenishment of filling, and means for actuating the movable member in backward and downward direction as the lay goes back and relative to the fixed member to form a plurality of bights in the old filling between the discharged filling carrier and shuttle and withdraw the old filling from the shuttle.

5. In a filling replenishing loom, a filling end withdrawing mechanism comprising a fixed member and a relatively movable member normally below the fixed member and mounted in front of the lay, means actuated on call for replenishment of filling for raising the movable member above the fixed member for engagement with and forward movement by the lay relative to the fixed member that it may engage the filling between the fixed member and shuttle as the lay goes back after replenishment of filling, and means for impulsively operating the movable member to form a plurality of bights in the filling between the ejected carrier and shuttle and whip the filling out of the shuttle.

35 6. In a filling replenishing loom, the combination with filling replenishing mechanism of a filling end withdrawing device, comprising a support at the front of the loom, a fixed clearer member extending rearwardly from the support and having a laterally extending rear end portion frontward of which the discharge filling carrier passes when it is ejected from the shuttle, a movable clearer member pivotally supported and having a laterally extended rear portion normally below the rear portion of the fixed member, means actuated on call for replenishment of filling for rocking the movable clearer member on its pivot to a position above the fixed clearer member that it may be engaged by and moved forwardly by the lay, and spring means for moving the movable clearer member backwardly and downwardly relative to the fixed clearer member as the lay goes back to withdraw the filling end of an ejected filling carrier from the shuttle.

7. In a filling replenishing loom, the combination with filling replenishing mechanism of a filling end withdrawing device, comprising a support at the front of the loom, a fixed clearer member extending rearwardly from the support and having a laterally extending rear end portion frontward of which the discharged filling carrier passes

when it is ejected from the shuttle, a movable clearer member pivotally supported and having a laterally extended rear portion normally below the rear portion of the fixed member, means actuated on call for replenishment of filling for rocking the movable clearer member on its pivot to a position above the fixed clearer member that it may be engaged by and moved forwardly by the lay, and spring means for moving the movable clearer member backwardly and downwardly relative to the fixed clearer member as the lay goes back to withdraw the filling end of an ejected filling carrier from the shuttle, and stops for limiting the pivotal movement of the movable clearer member.

8. In a filling replenishing loom, the combination of filling replenishing mechanism, an old filling end withdrawing device comprising two relatively movable members mounted at the front of the loom and positioned on replenishment of filling to engage the old filling between the ejected filling carrier and shuttle, and a spring for relatively moving said members one past or beyond the other to form a plurality of bights in the old filling and withdraw it from the shuttle.

9. In a loom, the combination of filling replenishing mechanism, the lay having a shuttle-box provided with a discharge opening for an ejected filling carrier, a fixed clearer member mounted in front of the lay and passing rearward of the discharge opening in the shuttle-box as the lay beats up, a second clearer member also mounted in front of the lay and normally occupying a position below the other clearer member, and means for raising the second clearer member above the other clearer member on call for replenishment of filling for engagement and movement forwardly by the lay as it beats up, and yielding means for moving the second clearer member rearwardly and downwardly as the lay goes back.

10. In a loom, the combination of filling replenishing mechanism, the lay having a shuttle-box provided with a discharge opening for an ejected filling carrier, a support a clearer member mounted on said support in front of the lay to pass rearwardly of the discharge opening in the shuttle when the lay beats up and the filling is to be changed, a second clearer member mounted in front of the lay and moved forwardly thereby on call for replenishment of filling, and means for moving the second clearer member rearwardly as the lay goes back and causing it to form a plurality of bights in the filling between the discharge bobbin and shuttle.

11. In a loom, the combination of filling replenishing mechanism, the lay having a shuttle-box provided with a discharge open-

- ing for an ejected filling carrier, a support 5 a clearer member mounted on the support in front of the lay to pass rearwardly of the discharge opening in the shuttle when the lay beats up and the filling is to be changed, a second clearer member mounted in front of the lay and moved frontwardly thereby on call for replenishment of filling, and means for causing the second clearer member to move rearwardly and past the other clearer member when the lay goes back to engage and form a plurality of bights in the old filling and withdraw it from the shuttle.
- 15 12. In a loom, the combination of filling replenishing mechanism, the lay having a shuttle-box provided with a discharge opening, a support in front of the lay, a clearer member mounted on the support in front 20 of the lay and extending rearwardly beyond the discharge opening when the lay beats up to permit a discharged filling carrier to pass frontwardly thereof, a second clearer member which is placed in position 25 to be engaged and moved frontwardly by the lay on call for replenishment of filling, and means for causing the second clearer member to pass about the other clearer member as the lay goes back to form a plurality 30 of bights in the old filling between the ejected filling carrier and shuttle and withdraw the filling from the shuttle.
13. In a filling replenishing loom, a filling end withdrawing mechanism, comprising 35 a clearer member mounted in front of and extended rearwardly toward the lay that an ejected filling carrier may pass frontwardly thereof when the filling is changed, a second clearer member which is 40 moved frontwardly by the lay when filling is to be changed, and means for causing the second clearer member to follow the lay rearwardly for part of the lay movement and then move in another direction relative to the other clearer member to form 45 a plurality of bights in the filling and withdraw it from the shuttle.
14. In a filling replenishing loom, a filling end withdrawing mechanism comprising 50 a clearer member mounted at the front of the loom and extended rearwardly toward the lay to have an ejected filling carrier pass frontwardly of said member when the filling is changed, a second clearer member 55 which is moved frontwardly only on call for replenishment of filling, and means for causing the second clearer member to move rearwardly to engage the filling between the other clearer member and the shuttle and then to move in another direction relative to 60 the other clearer member to form a plurality of bights in the filling between the ejected filling carrier and shuttle.
15. In a filling replenishing loom, a filling end withdrawing mechanism, comprising a 65 clearer member mounted at the front of the loom and extended rearwardly toward the lay to have an ejected filling carrier pass frontwardly of said member when the filling is changed, a second clearer member mounted 70 for frontward movement on call for replenishment of filling, then a rearward movement to engage the filling after replenishment of filling has been effected and then a swinging movement for creating a 75 plurality of bights in the filling and withdraw it from the shuttle.
16. In a filling replenishing loom, a filling end withdrawing mechanism, comprising a clearer member mounted at the front of the 80 loom and extended rearwardly toward the lay to have an ejected filling carrier pass frontwardly of the clearer member when the filling is changed, a second clearer member, connections for placing the second clearer member in position to be moved frontwardly by the lay on call for replenishment of filling, a spring for moving the feeler rearwardly a part of the lay movement as the lay goes back that it may engage 85 the filling, and yielding means for moving the second clearer member in another direction to form a plurality of bights in the filling about the clearer members.
17. In a filling replenishing loom, a filling end withdrawing mechanism, comprising a clearer member mounted at the front of the loom and extended rearwardly toward the lay to have an ejected filling carrier pass frontwardly of the clearer member when 90 the filling is changed, a second clearer member normally occupying a position of non-contact by the lay on a beat-up, an arm actuated on call for replenishment of filling to position the second clearer member for 95 engagement by a part on the lay and effect frontward movement thereof, means for causing the second clearer member to follow the lay rearwardly part of the lay movement and thereupon to become disengaged 100 from the lay part and move in another direction to form a plurality of bights in the filling.
18. In testimony whereof, I have signed my name to this specification.

CONRAD BELISLE.
